Specification for Design.

Patented July 9, 1912.

Application filed February 13, 1912. Serial No. 677,365. Term of patent 14 years.

To all whom it may concern:

Be it known that I, WILLIAM FREDERICK PFEIFFER, a citizen of the United States, and resident of Akron, in the county of Summit and State of Ohio, have invented a new, original, and ornamental Design for Elastic Tires for Vehicles, of which the following is a specification, reference being had to the accompanying drawings, forming part thereof.

In the drawings, Figure 1, is a perspective

view of an elastic tire for vehicles, showing my new design; and Fig. 2, is a plan of a portion of the tread of said tire illustrating my new design.

I claim:

The ornamental design for an elastic tire for vehicles, as shown.

WILLIAM F. PFEIFFER.
